(57) **CLAIM**

The ornamental design for a beverage jug, as shown and described.

DESCRIPTION

FIG. 1 is a front side perspective view of our new beverage jug;

FIG. 2 is a front elevation view thereof;

FIG. 3 is a rear elevation view thereof;

FIG. 4 is a left elevation view thereof;

FIG. 5 is a right elevation view thereof;

FIG. 6 is a bottom plan view thereof; and,

FIG. 7 is a top plan view thereof.

The broken line showing is for illustrative purposes only and forms no part of the claimed design.
